Application June 24, 1949, Serial No. 3,508

Term of patent 14 years

(Cl. D44—22)

To all whom it may concern:

Be it known that we, Adrienne Brita Juvet Dokus and John Ivan Dokus, citizens of the United States of America, residing at Newark, in the county of Essex and State of New Jersey, have invented a new, original, and ornamental Design for Multiple Condiment Holder, of which the following is a specification, reference being had to the accompanying drawing, forming a part hereof.

In the drawing:

Fig. 1 is a front perspective view of a multiple condiment holder, showing our new design;

Fig. 2 is a rear perspective view; and

Fig. 3 is a top plan view thereof.

We claim:

The ornamental design for a multiple condiment holder, substantially as shown.

ADRIENNE BRITA JUVET DOKUS.
JOHN IVAN DOKUS.
